(57) **CLAIM**

We claim the ornamental design for a fabric panel, as shown and described.

DESCRIPTION

The patent or application file contains at least one drawing executed in color. Copies of this patent or patent application publication with color drawing(s) will be provided by the Office upon request and payment of necessary fee.

FIG. 1 is an isometric view looking downwardly at the front of the panel in an open condition.

FIG. 2 is an isometric view similar to FIG. 1 looking upwardly from the rear of the panel.

FIG. 3 is a front elevation view of the panel of FIG. 1.

FIG. 4 is a rear elevation view of the panel of FIG. 1.

FIG. 5 is a right side elevation view of the panel of FIG. 1 with the left side elevation being a mirror image thereof.

FIG. 6 is a top plan view of the panel of FIG. 1.

FIG. 7 is a bottom plan view of the panel of FIG. 1.

FIG. 8 is an isometric view similar to FIG. 1 looking downwardly at the front of the panel but in a closed position.

FIG. 9 is an isometric view looking upwardly at the rear of the panel of FIG. 8.

FIG. 10 is a front elevation view of the panel of FIG. 8.

FIG. 11 is a rear elevation view of the panel of FIG. 8.

FIG. 12 is a right side elevation view of the panel of FIG. 8, with the left side elevation being the mirror image thereof.

FIG. 13 is a top plan view of the panel of FIG. 8; and,

FIG. 14 is a bottom plan view of the panel of FIG. 8.
